UNITED STATES PATENT OFFICE

ALBERT S. RIVIERE AND CHARLES F. RUBEL, OF CHICAGO, ILLINOIS, ASSIGNORS TO UNION SPECIAL MACHINE COMPANY, OF CHICAGO, ILLINOIS, A CORPORATION OF ILLINOIS

FLAT SEAM SEWING MACHINE

Application filed September 12, 1928. Serial No. 305,435.

The invention relates to new and useful improvements in sewing machines, and more particularly to a sewing machine for uniting fabric sections so as to form a flat covered seam.

An object of the invention is to provide a machine of the above type having a rib on the work supporting arm for guiding the upturned edge portions of fabric sections where-

10 in the rib is supported so that it may be moved away from the presser foot to facilitate the passing of cross seams, elastic tapes or the like beneath the presser foot.

15 A further object of the invention is to provide a machine of the above type wherein the presser foot is formed with a yielding section in rear of the needles, which yielding section may move above the surface of the presser foot or beneath the surface of the 20 presser foot to aid in the control of the fabric during the passing of cross seams, elastic tapes and the like.

25 A still further object of the invention is to provide a machine of the above type wherein in the yielding section of the foot is cut away immediately in rear of the needles so as to provide clearance for the needle thread during chaining.

These and other objects will in part be 30 obvious and will in part be hereinafter more fully disclosed.

In the drawings which show by way of illustration one embodiment of the invention—

35 Figure 1 is a side view of a portion of a machine having the improvements applied thereto;

Fig. 2 is a plan view of the presser foot, also showing the position of the cross thread laying devices and the trimming devices, and more particularly the rib which guides the up-turned edge portions of the fabric sections;

40 Fig. 3 is an enlarged view showing more or less diagrammatically the presser foot, the trimming blades, the guiding slot for directing the upturned edge portions, and the rib for guiding said edge portions, with the rib in forward operating position;

45 Fig. 4 is a view similar to Fig. 3, but show-

ing the rib retracted so as to permit a cross seam, elastic tape or the like to pass beneath the foot;

Fig. 5 is a side view showing more or less diagrammatically the presser foot, the yielding section in rear of the needles, and the position of the parts when the elastic tape is passing beneath the forward portion of the foot;

Fig. 6 is a similar view, but showing the position of the parts when the elastic tape is passing beneath the yielding section of the foot;

Fig. 7 is a bottom plan view of the presser foot;

Fig. 8 is a perspective view of the rib which guides the upturned edge portions of the fabric sections;

Fig. 9 is a view showing more or less diagrammatically, and partly in section, the forward end of the presser foot, a portion of the work support and the rib, and the manner of guiding the upturned edge portions, and

Fig. 10 is a sectional view through the shank of the presser foot, showing the manner of supporting the yielding section.

The invention is directed to a sewing machine which is especially adapted for joining the edge portions of knitted fabrics for forming therein a flat seam. The edge portions of the fabric sections are upturned, and one or both of the edges are trimmed, after which they are turned down into flat relation and either abutted, or one of the edge portions slightly overlapping the other. As thus positioned, the fabric sections are directed to a stitch forming mechanism which includes a plurality of needles disposed so as to join the edge portions of fabric sections, and cooperating with these needles is a cross thread laying mechanism on the upper face of the material, and a looper beneath the material, and this forms a flat covering seam. The seam produced on the machine is similar to that disclosed in the patent to Joseph Berger No. 1,349,712, granted August 17, 1920. The present machine is particularly adapted for stitching relatively thin material, such as rayon silk. The presser foot is provided with a guiding slot through which the

80

85

90

95

100

upturned edge portions of the fabric sections are directed to the trimming mechanism. To aid in guiding these upturned portions, the work support is provided with a 5 rib which extends into a slot or channel in the presser foot. This rib is mounted on a supporting member which is capable of sliding lengthwise of the work supporting arm. When a heavy cross seam or a pocket 10 containing a heavy cross elastic tape approaches the presser foot, it is practically impossible to cause it to pass into the slot and beneath the presser foot with the rib extending into said channel or slot which receives the upturned edge portions. The machine is, therefore, stopped, and the support for the rib slides along the work supporting arm so as to move the rib out of the channel or slot in the presser foot, and a sufficient distance away from the 15 presser foot to permit this heavy cross seam or elastic tape to pass underneath the presser foot. The presser foot is provided with a yielding section in rear of the needles which extends all the way across the foot, and this 20 yielding section is capable of movement so that its under face is above the plane of the bottom of the foot, or under other conditions, it is beneath the plane of the presser foot. This yielding section is also provided with a 25 clearance space directly in rear of the needles.

Referring more in detail to the drawings, the machine to which the invention is applied includes a work supporting arm 1 in which is mounted the looper mechanism and the feeding mechanism. The looper mechanism includes a looper 2 of the thread carrying type. Directly above the free end of the work supporting arm is a needle head in which the needle bar reciprocates, and in the 40 present embodiment of the invention, the needle bar is provided with three needles 3, 3, 3.

The looper cooperates with all three needles. The material is held on the work 45 support by a presser foot 4. Mounted on the presser foot 4 is a stationary trimming blade 5, and cooperating with this stationary trimming blade is a movable blade 6. A cross thread guide 7 directs the cross thread 50 so that it is engaged by a hook 8. This hook forms a loop in the cross thread which is secured by the needle threads. This cover stitch forming mechanism is of the usual type, and further description thereof is not 55 thought necessary. The presser foot is provided with a channel or slot 9 into which the upturned edge portions of the fabric sections are led. This slot directs the edge 60 portions of the trimming devices which trim one or both of the edge portions. Mounted on the work supporting arm 1 is a rib 10. This rib extends into the channel or slot in the presser foot and is provided with a finger 65 11 which holds the right-hand fabric section, as viewed in Fig. 9, raised while the edge

portion of the other fabric section is being turned down into flat position. After one edge portion is turned down into flat position, the other edge portion passes off from this finger and is likewise folded down on to the first-named edge portion. These edge portions, as noted, may slightly overlap, or may be abutted. It is preferred to overlap the sections, and therefore, the rib is provided so as to positively insure the turning down of one edge portion and then the other on to the same. The rib is cut away as indicated at 12, and is tapered off as indicated at 13 to allow the left-hand edge portion to first turn down into a flat position, while the other section is being held by the finger 11. The presser foot is provided with stitch fingers 14 which are carried by a bridging portion which aids in the turning down of the fabric sections. These parts of the presser foot which turn down the edge portions and control the same, may be of any well known construction. The present invention is directed more particularly to the mounting of the rib and the construction of the presser foot so as to provide a yielding section extending all the way across in rear of the needles.

The rib 10 is mounted on a support 15 which in turn is mounted in a recess 16 in the work supporting arm. This support slides endwise in this recess. When the rib is at the forward end of its movement on the work support, it lies well within the channel or slot of the presser foot, and performs its function of guiding the upturned edge portions of the fabric sections. There are times when very heavy cross seams must be passed beneath the presser foot to complete the seam which is being formed on the garment. There are also times when elastic tapes running at right angles to the seam being formed must be passed beneath the presser foot. The machine is particularly designed for stitching relatively thin fabrics, such as rayon silk and the like, and therefore, the clearance space between the rib and the adjacent walls of the presser foot is necessarily limited so that if a cross seam or an elastic tape passes underneath the foot, it is likely to be jammed between the rib and the foot, or if it passes beneath the foot, the foot is raised to such an extent as to lose its control of the material being stitched. When these heavy cross seams approach the presser foot, the machine is stopped, and the support for the rib is moved along the work supporting arm to its full retracted position. This moves the rib out of the channel, or slot in the presser foot, and thus gives ample clearance space to permit the cross seam to pass beneath the foot and the edge portions of the cross seam to be firmly joined.

The presser foot is provided with a yielding section 17 which extends all the way

across the foot. This yielding section 17 is carried by two spaced vertical members 18, 18, which are mounted to slide in suitable guideways in the sides of the shank of the 5 presser foot. A screw 19 passing through the slot in one of these vertical members and threaded into the shank, limits the movement of the vertical member on the shank. Springs 20, 20 are carried by the presser foot and bear 10 on the yielding section 17. The presser foot has a cut-away portion for forming a space in which this yielding section is located. The yielding section, when at the extreme upper 15 end of its movement, is housed within this recess and the lower face of the yielding section is above the plane of the bottom of the presser foot. When the yielding section is all the way down, then the bottom face of the yielding section is below the plane of the 20 bottom of the presser foot. When the cross seam passes the needles, and is fed underneath this yielding section, the yielding section will move up, resting on top of the cross seam, while the front part of the presser foot 25 will move down so as to contact with the material following the cross seam. Thus it is that the material following the cross seam will be properly held down on the cloth plate during the entering of the needles into and 30 out of the fabric, and there will be no vibrating or drum heading of the fabric. On the other hand, when the cross seam first passes beneath the presser foot, the front portion of the presser foot is raised, and the yielding 35 section will move down so as to engage a fabric passing in advance of the cross seam and insure a proper feeding of the fabric, and also a proper chaining between articles.

This yielding section 17 of the presser foot 40 is formed with a clearance space 21. The purpose of this clearance space is to reduce the extent to which the feed dog engages the en-chained thread loops and give clearance for the chain so as to prevent the same from being 45 cut by the feed during chaining off.

It is obvious that minor changes may be made in the details of construction and the arrangement of the parts without departing from the spirit of the invention as set forth 50 in the appended claims.

Having thus described the invention, what we claim as new and desire to secure by Letters-Patent, is—

1. In a sewing machine, the combination 55 of a work supporting arm, a presser foot having a channel for receiving and directing the upturned edge portions of fabric sections, trimming devices associated with the presser foot for trimming the upturned edge portions, cover stitch forming mechanism for 60 joining and covering said edge portions, a rib mounted on said work supporting arm and extending into said channel of the presser foot for guiding the upturned edge portions, and means whereby said rib may be with- 65

drawn from the channel in the presser foot to permit the passing of cross seams beneath the presser foot.

2. In a sewing machine, the combination of a work supporting arm, a presser foot having a channel for receiving and directing the upturned edge portions of fabric sections, trimming devices associated with the presser foot for trimming the upturned edge portions, cover stitch forming mechanism for 70 joining and covering said edge portions, a rib mounted on said work supporting arm and extending into said channel of the presser foot for guiding the upturned edge portions, said rib having a projecting finger and a cut-away portion alongside thereof to aid in the placing of the edge portions of the fabric sections one on the other, and means whereby said rib may be withdrawn from the channel 75 to permit a cross seam to pass beneath the presser foot. 80

3. In a sewing machine, the combination of a work supporting arm, a presser foot having a channel for receiving and directing the upturned edge portions of fabric sections, trimming devices associated with the presser foot for trimming the upturned edge portions, cover stitch forming mechanism for joining 90 and covering said edge portions, a rib extending into the channel in the presser foot 95 for guiding and supporting the upturned edge portions of fabric sections, a support on which said rib is mounted, said work supporting arm having a recess in which said support is mounted for movement lengthwise of the 100 work supporting arm so as to position the rib in the channel on the presser foot or withdraw it from said channel. 105

4. In a sewing machine, the combination of a work supporting arm, a presser foot having a channel for receiving and directing the upturned edge portions of fabric sections, horizontally disposed trimming devices movable up and down with the presser foot for trimming said edge portions, cover seaming mechanism for joining and covering the edge portions after they are trimmed, said presser foot having a cut-away portion in rear of the stitching mechanism, and a yielding section located therein and extending all the way 110 across the presser foot, said yielding section being capable of movement above and below the plane of the bottom of the presser foot. 115

5. In a sewing machine, the combination of a work supporting arm, a presser foot having a channel for receiving and directing the upturned edge portions of fabric sections, horizontally disposed trimming devices movable up and down with the presser foot for trimming said edge portions, cover seaming mechanism for joining and covering the edge portions after they are trimmed, said presser foot having a cut-away portion in rear of the stitching mechanism, a yielding section located in said cut-away portion and extending 120 125 130

- all the way across the presser foot, vertical members rigid with said yielding section and disposed in guiding recesses in the shank of the presser foot, one of said vertical members having a slot therethrough, a screw extending through the slot for limiting the movement of the yielding section, said yielding section being adapted to move above and below the plane of the bottom of the presser foot, and a spring for normally depressing said yielding section.
6. In a sewing machine, the combination of a work supporting arm, a presser foot having a channel for receiving and directing the upturned edge portions of fabric sections, horizontally disposed trimming devices movable up and down with the presser foot for trimming said edge portions, cover seaming mechanism for joining and covering the edge portions after they are trimmed, said presser foot having a cut-away portion in rear of the stitching mechanism, a yielding section located in said cut-away portion and extending all the way across the presser foot, a spring for depressing said yielding section, means for limiting the movement of the yielding section whereby it may move across the plane of the bottom of the presser foot.
7. In a sewing machine, the combination of a work supporting arm, a presser foot having a channel for receiving and directing the upturned edge portions of fabric sections, horizontally disposed trimming devices movable up and down with the presser foot for trimming said edge portions, cover seaming mechanism for joining and covering the edge portions after they are trimmed, said presser foot having a cut-away portion in rear of the stitching mechanism, a yielding section located in said cut-away portion and extending all the way across the presser foot, a spring for depressing said yielding section, means for limiting the movement of the yielding section whereby it may move across the plane of the bottom of the presser foot, said yielding section having a clearance space formed in the bottom thereof at the front side thereof directly in rear of the needles of the stitching mechanism so as to give clearance for the chain in chaining off.
8. In a sewing machine, the combination of a work supporting arm, a presser foot having a channel for directing the upturned edge portions of fabric sections, horizontally disposed trimming devices movable up and down with the presser foot for trimming said edge portions, cover stitch forming mechanism located in rear of the trimming devices, a rib mounted on said work support and extending into said channel for guiding and supporting the edge portions, means for supporting said rib whereby it may be withdrawn from the channel, said presser foot having a cut-away portion in rear of the stitch forming mechanism, a yielding section located in

said cut-away portion and extending all the way across the presser foot, and means for limiting the movement of said yielding section whereby it may be moved across the plane containing the bottom of the presser foot.

In testimony whereof we affix our signatures.

ALBERT S. RIVIERE.
